UNITED STATES PATENT OFFICE.

EDWARD J. GULICK, OF ELKHART, INDIANA.

HORN BELL.

Application filed April 3, 1926. Serial No. 99,436.

My invention relates to wind musical instruments of the horn type, and especially to the horn bell of the bass and other very large horns.

5 The bell of the bass horn, as it has been built, is made of very thin sheet metal, preferably brass, is very large in diameter, fragile, easily bent or warped or dented, and readily subject to audible vibration when the 10 instrument is played.

The object of my invention is to provide a reinforced horn bell which will not warp or distort under changes of temperature, or emit audible vibration when the player uses the 15 instrument.

The preferred embodiment of my invention is illustrated in the accompanying drawing in which Figure 1 is a front elevation of a bass horn bell to which my invention is applied; Figure 2 is a vertical cross-section taken through the bell at right angles to Fig. 1; Fig. 3 is a plan view of one of the reinforcing rings; and Fig. 4 is a section taken on line 4—4 of Fig. 3.

25 Similar numerals of reference indicate like parts throughout the several views on the drawing.

Referring to the details of the drawing the numeral 1 indicates the curved tubular body 30 of a bass horn which terminates in the usual large belled section 2 which, in bass horns, and the like, is very large in diameter, fragile, easily bent or warped, and, without some reinforcing means, will readily emit audible vibration when the instrument is played.

When the horn bell is provided with my improved reinforcing means, as hereinafter described, it becomes much more stable in every respect, and does not give forth audible vibration when the instrument is played. By 40 extensive tests I have found that the most effective reinforcing means comprises a plurality, or series, of circular, or elliptical metal rings or strips 3, 4, 5 and 6 arranged around 45 the horn bell interior and soldered or brazed thereto at spaced intervals, although said reinforcing elements may be secured to the horn bell exterior with equal effect and success.

And while I show elements 3 and 5 to be substantially elliptical ring-like members, and elements 4 and 6 to be substantially circular, it is to be understood that the entire series 50 of reinforcing elements may be composed of either form to the exclusion of the other,

with very good results, and that it is the intent to apply either or both forms in the practical use of the invention.

Each of the ring-like reinforcing members 3, 4, 5 and 6 is preferably made of a strip of flexible metal, preferably brass, bent to the 55 desired circular or elliptical form, as well as laterally to conform with the curve of the horn bell, and butt welded or soldered and plated to insure a smooth and invisible joint, the top surface of the strip being preferably 60 somewhat convex and the bottom surface flat to facilitate contact with the bell surface.

I claim:

1. A bell for a wind musical instrument of the class described provided with a series 70 of bent reinforcing strips arranged around the bell surface and permanently secured thereto.

2. A bell for a wind musical instrument of the class described provided with a series 75 of reinforcing strips bent longitudinally and laterally to conform to the bell curve and arranged in spaced order around the instrument bell and secured thereto by metallic cement.

3. A bell for a wind musical instrument of the class described provided with a series 80 of curved reinforcing strips arranged around the bell surface and permanently soldered thereto.

4. In a bell for a wind musical instrument of the class described, a reinforcing means for said bell and comprising a strip of metal bent longitudinally and laterally thereof to conform to the curve of the bell and permanently secured to the bell by metallic cement.

5. In a bell for a wind musical instrument of the class described, a reinforcing means for said bell and comprising a strip of metal bent longitudinally and laterally thereof to 95 conform to the curve of the bell and having its ends united to form an endless element, said reinforcing element being soldered to the face of the bell.

6. A bell for a wind musical instrument of 100 the class described provided with a series of curved reinforcing strips of various shapes arranged around the bell and permanently soldered thereto in spaced relation.

7. In a bell for a wind musical instrument 105 of the class described, reinforcing means for said bell and comprising a strip of metal bent longitudinally and laterally thereof to con-

form to the curve of the bell and secured to the bell interior by metallic cement.

8. In a bell for a wind musical instrument of the class described, reenforcing means for said bell and comprising a strip of metal of irregular formation, bent to conform to the curve of the bell and secured to the interior surface thereof by metallic cement.

9. In a bell for a wind instrument of the class described, reenforcing means for said bell and including a strip of metal secured to the bell surface by metallic cement and en-

gaging a fragment only of the diametrical extent of the bell surface.

10. A bell for a wind musical instrument of the class described and provided with a series of reenforcing metal strips arranged around the interior surface of the bell and angularly of the axis thereof, said strips being permanently secured to the bell by metallic cement.

In witness whereof I have hereunto affixed my signature this 1st day of April, 1926.

EDWARD J. GULICK.
